UNITED STATES PATENT OFFICE.

HENRY GEORGE ABRAHAM ISAAC WIEDER, OF LONDON, ENGLAND.

STETHOSCOPE.

SPECIFICATION forming part of Letters Patent No. 779,144, dated January 3, 1905.

Application filed December 3, 1903. Serial No. 183,679.

To all whom it may concern:

Be it known that I, HENRY GEORGE ABRAHAM ISAAC WIEDER, a subject of the Emperor of Austria-Hungary, and a resident of 6 White 5 Lion street, Bishopsgate, London, in the county of Middlesex, England, have invented new and useful Improvements in Stethoscopes and other Instruments for Rendering Weak Sounds Distinctly Audible, of which the following is a specification.

My invention relates to stethoscopes or instruments for rendering easily audible weak sounds in the human body or to instruments of similar kind, such as ear-trumpets and the like, used for rendering more audible other sounds in which a diaphragm caused to vibrate by the sounds is used; and the objects of my invention are, first, to provide means by which the diaphragm is highly stretched 15 and rendered very tense and sensitive; second, to collect and direct upon the diaphragm the sound-vibrations received, and, third, to prevent the interference of extraneous sounds with those received and reproduced by the instrument. I attain these objects by the means 20 illustrated in the accompanying drawings, in which—

Figure 1 is a section through the center of the instrument, and Fig. 2 is a view from the 25 back.

a is a very thin circular disk or diaphragm, of metal or other suitable material, the edge of which is fitted into the inner edge of a cylindrical ring *b*, of brass or other metal or 30 material.

c is an outer cylindrical case, of ebonite or other like suitable material, having a cylindrical recess at *d*, into which the ring *b* and diaphragm *a* fit and are inserted, resting 35 against a narrow shoulder at *d* on the inner side of the case *c*. Inside the ring *b* is fitted a circular flat plate *e*, of metal or other hard material, having a small slightly-projecting rim round its upper edge at *f*, which when 40 inserted in its place presses against and holds the edge of the ring *b* and diaphragm *a*, giving the latter a very rigid tension and leaving a very narrow space at *g* between it and the face of the plate *e*, which has also an outer 45 flange, the edge of which is level with the

outer edge of the ring *b*, both being some distance inside the outer edge of the flange of the case *c*, which is screwed inside with a fine thread to receive a corresponding ring *h*, the outer edge of which is milled at *i*, so that it 55 can be readily screwed in with the fingers to fix the ring *b* and diaphragm *a* or unscrewed when required.

The back of the plate *e* has at its center a projecting tubular boss *j*, upon which can be 60 screwed a junction-piece *k*, having two branches *l* *l'*, to which flexible tubes can be easily attached and brought to the ears of the listener.

In order to obtain the highest efficiency, the 65 central part of the diaphragm *a* must be rendered quite rigid and incapable of independent vibration and only the part between such rigid center and the edge must communicate its vibrations to the air in the space between 70 the diaphragm *a* and the plate *e*.

In order to insure the perfect rigidity of the central part of the diaphragm *a*, upon which is fitted the open wide end of the thin metal cone *m*, upon the apex of which is fixed 75 the smaller inverted cone *n*, a slightly curved or arched metal disk *p* is arranged across the back of the diaphragm *a*, against which it can be tightened with any desired force by a central bolt *q*, the enlarged cylindrical head of 80 which, *r*, fits into the bottom of the small cone *n*, through which it passes, while its top *r'* is curved or spherical in shape. The cone *m* distributes the sound-waves equally all round the diaphragm, while the top receives the 85 sound.

The bolt *q* passes centrally through the cones *m* and *n*, the diaphragm *a*, and the curved disk *p*, which latter is forced up by tightening the nut *s* (through the opening in the boss *j*) until the center of the diaphragm *a* is drawn up into the mouth of the cone *m*, as shown, by the curved disk *p*, the said central part being thus made rigid and non-vibrating and the loudness and clearness of the sounds 95 produced by the instrument being enormously increased. This arrangement is essential to the perfect working of the instrument.

The spherical top *r'* of the bolt *q* projects slightly beyond the edge of the cone *n*, which 100

is pressed gently upon the surface—such as the human breast—the sound from or near which is to be transmitted through the tubes $l l'$ to the ear of the listener.

- 5 The outer part of the case c is formed as a cone u , the small open end of which surrounds freely the small cone n and the bolt-head r . This outer cone u forms a perfect protection to the diaphragm and to the two cones, while 10 occupying very little space. It also serves to protect the diaphragm from any sound or noise going on outside the sphere of the sounds which it is desired to hear, so that it is possible to hear the desired noises very distinctly, 15 but not other noises which are continually going on around.

For greater convenience and comfort I make a ring t , of soft india-rubber or the like material and of suitable shape, upon the outer 20 edge of the cone u of the case, which can be pressed into more close contact with the body without inconvenience. For some medical or other purposes, such as for stethoscopes, the spherical top r' of the bolt q (or a sufficiently 25 long rigid projecting rod, which may be screwed upon it or form part of it) and the edge of the small cone n are held against or near the position of origin of the sound to be magnified—as, for instance, the chest, opposite 30 the heart or lungs—and the outer end of the flexible tubes (or of one of them) are held in the ears, (or ear.)

The whole apparatus is purely mechanical,

there being no magnet of any kind nor any electricity used.

35

I am aware that instruments have been made in which the center of the diaphragm a is provided with a rigid cone, such as m , having an inverted cone, such as n , on its summit, and I do not, therefore, claim such a combination broadly; but

40

What I claim, and desire to secure by Letters Patent, is—

1. The combination of the diaphragm a , ring b , outer case c , recess d , screwed ring h , 45 plate e , hollow boss j , cone m , inverted cone n , curved disk p , bolt q , cylindrical rounded head r , and nut s , all substantially as set forth.

2. The combination of a thin diaphragm a 50 rigidly held at its outer edge, a hollow cone n fitting against the center of the outer side of the diaphragm, a curved disk p fitting against the inner side of the diaphragm a , a central bolt q passing through the center of the cone 55 m , the diaphragm a and the curved disk p , a cylindrical head having a rounded top r' on the outer end of the bolt, and a screwed nut s at the inner end of the bolt, all substantially as set forth.

55

In witness whereof I have hereunto set my hand in the presence of two witnesses.
